PORTABLE PRINTING DEVICE

Gerhard G. Gruettner, New York, N. Y.

Application May 16, 1939, Serial No. 273,832

4 Claims. (Cl. 101—287)

This invention generally relates to printing devices of the portable type and more particularly to a check-signing equipment for use by banks, industrial concerns, etc.

It is an object of the present invention to provide an efficient, practical and economical portable electric device of the above nature for printing indicia or the like.

It is a further object of the present invention to incorporate in such a device means to maintain in operative position an indicia carrying plate, as, for example, a signature plate, employed preferably for check-signing purposes, which plate is so located as to prevent tampering therewith.

Still another object of the invention is to provide means to lockingly position said plate in the frame of the device.

Yet another object of the present invention resides in the provision of automatic feeding means for the printing ribbon to enable reverse rotary movement of the printing ribbon during its operation and at predetermined period.

It is a still further object of the present invention to incorporate in said automatic means a pair of carriers for said ribbon controlled by a regulating mechanism to properly feed said ribbon from one carrier to the other and to predeterminedly reverse said ribbon movement.

Still another object of the present invention is to provide feelers cooperating with the portions of the ribbon on said carriers which feelers make operative the reversal of said ribbon movement.

It is still another object of the invention to provide means to momentarily maintain contact between signature plate, check paper and ribbon in order to achieve a clear and strong impression of the indicia to be transferred to the paper.

It is a further purpose of the invention to provide switching means to interrupt operation of the machine either combined with or independent of the plate locking mechanism.

Accordingly, the invention consists in the features of construction, combination of elements and arrangements of parts, all as will be illustratively set forth in the following description, and the scope of the application of which will be indicated in the appended claims.

With these and other objects in view there has been illustrated on the accompanying drawings one form in which the invention may be conveniently embodied in practice.

In the drawings:

Fig. 1 is a front end view of a printing device embodying the invention;

Fig. 2 is a fragmentary rear view partly in section showing one of the locking mechanisms;

Fig. 3 is a rear end view of the device, shown in Fig. 1;

Figs. 4 and 5 are two different diagrams showing electrical connections employable in the said device;

Fig. 6 is a vertical sectional view taken along line 6—6 of Fig. 3;

Fig. 7 is a partial sectional view in diagrammatic form of a combined locking mechanism.

Referring now to the drawings which show one of the various possible examples for carrying out the invention, there is disclosed a housing 10 comprising a base 11, side walls 12, 13, respectively, and a cover 14 which extends substantially from the front across the top and rear to the base 11 as clearly shown in Fig. 6.

Side walls 12 and 13 have longitudinal horizontal cut-outs 15, 16 in which protrudes a platform 17 secured by any suitable means, such as set screws (not shown) to lugs 18 extending outwardly from the side walls 12, 13.

Platform 17 has a cut-out 19 which extends from the rear edge thereof to an edge of the platform within the limits of the said side walls, thus providing a free space for the operating mechanism as hereinafter described. The remaining portion 21 of the platform 17 is utilized

as a support for the paper to be imprinted or embossed during operation of the device. One of the extending lateral portions of said platform 17 carries a slide 22 which is adjustable with respect to the platform as by means of set screws 23.

Slide 22 has at its inner end a transverse bar 24 forming an abutment and guide for the paper P to be fed into the device for the printing or like purpose.

Arranged within cut-out or opening 19 is a vertically slidable platen 25 for raising the paper P against the printing ribbon 26 extending over the indicia plate 27 which is slidably insertable into the slideway 28.

Platen 25 is supported on a plunger 29 vertically extending within the winding (not shown) of and forming the core of a solenoid 30 in a casing 31. Across the top of solenoid casing 31 is placed a cover plate 32 secured to inwardly extending side wall flanges 33 as by means of screws 34. Plate 32 has a perforation 35 through which extends from the underside of platen 25 and for guidance pin 36. Platen 25 is provided on its top face with a cushion plate or pad 37 made of any suitable material.

Secured to base 11 at the slot 39, by means of screws 41', is a block 40. Block 40, the extension 45 of the casing 31 have aligned slots 40' and 44. Plunger core 29 projects through casing 31 and extends beyond the same and within base slot 39 when the platen 25 is in inoperative position. This extended portion of the core 29 also has a slot 29' in alignment with the aforementioned slots 40' and 44. Pivoted about pin 41 in block slot 40' is a lever arm 42, which extends from said block slot through plunger core slot 29' in which said arm is pivotally fixed as by means of pin 43. The free end of arm 42 is pivotally connected at 46 with a rod 47 which projects upwardly in the machine housing.

Vertical movement of core or plunger 29 is controlled by the field excitation of said solenoid 30, the latter being in turn controlled by means of a switch arrangement hereinafter fully described.

It is evident that vertical upward movement of plunger 29 will cause swinging movement of arm 42 about pivot 41 which latter motion is translated through rod 47 to a lever 48. Spring 49 having one of its ends attached to leverage 48 and its other end being secured to base 11 by means of bracket 50 and lug 51 urges return movement of plunger 29 when the switch cuts off the current supply to the solenoid 30.

Lever 48 has a reduced portion 52 to which said spring 49 is attached at 53 and rod 47 at 54, and an enlarged portion 55 the free end of which is fixed to a shaft 56 journaled in bearing 57 formed in upwardly extending brackets 58 which may form part of an abutment plate 59 secured to inwardly protruding lugs 60 of side walls 12, 13.

Abutment plate 59 is provided with upwardly extending pairs of lugs 61, 61', 62, 62', respectively. In the rear of 61' and 62' and spaced therefrom are also upwardly extending lugs 63, 64, the height of which is somewhat less than that of lugs 61', 62'. Journaled in the pair of lugs 61, 61' and the lug 63 is a shaft 65 upon which is rolled one end of the ribbon 26, the other end of said ribbon being rolled upon another shaft 66 journaled in the lugs 62, 62' and lug 64.

Interposed between lugs 61' and 63 and fixed to shaft 65 is a ratchet wheel 67 engageable by a dog 68 pivoted to an arm 69 the free end of which is pivoted to lug 61', the other end of which arm is provided with an elongated slot 70 through which projects the reduced portion 52 of lever 48. Interposed between lugs 62' and 64 and fixed to shaft 66 is another ratchet wheel 67' engageable by a dog 68' mounted for pivotal movement on arms 69', the free end of which is pivoted at lug 62', the other end of which arm is provided with an elongated slot 70' through which projects the reduced portion 52 of lever 48.

Between arm 69 and enlarged portion 55 of lever 48 there is provided on said reduced portion 52 a shield plate 71 which slides with said lever 48 upwardly and downwardly during operation of said machine. Plate 71 is laterally guided in an angle piece 72 which is placed on the abutment plate 59 and fixed thereto. Abutment plate 59 has a recess 74, and portion 75 of angle piece 72 is provided with a slot 76' the end of which is somewhat enlarged to laterally guide therein said aforementioned plate 71 and within said recess 74.

The upwardly directed portion 76 of angle piece 72 is slotted at 77 to permit guidance of

the enlarged portion 55 of lever 48 therein, when said lever 48 achieves its movements during operation. Pivoted to portion 76, as at 78, 78' are respective bell crank levers 79, 79' the free ends of which are provided with angularly bent portions 80, 80' and 81, 81'. Portions 80 and 81 are flat and adapted to contact rolled ribbon parts 82, 82' on shafts 65, 66. To this end, a spring 83 which is secured at 84 to upwardly extending angle piece portion 76 engages with its free and bent ends said bell crank levers 79, 79' to permanently urge their flattened portions 80 and 81 to rest on ribbon parts 82, 82'.

Shield plate 71 carries pivotally (at 73) attached thereto a rocker 85 for a purpose herein-after further described. Rocker 85 which is substantially triangular in shape has an outwardly extending pin 86 at its apex 87, which pin is adapted to engage selectively the legs 88, 88' of a U-shaped spring member 89, the latter being fixed to an extension 90, as by means of set screw 91, of a bar 92 which pivotally connects with the ends of said dogs 68, 68' whereas the free ends of said dogs are selectively engageable with the aforementioned ratchet wheels 67, 67'.

On shield plate 71 there extends a pin 93 to which is fixed one end of a helical spring 94, the other end thereof being attached to said pin 86 of said rocker 85. The purpose of this spring 94 is to maintain said rocker 85 in either of its extreme positions when thrown as about to be described.

Bell crank levers 79, 79' have as aforesaid the portions 80', 81' the ends of which are inturned toward the rocker 85 the latter carrying two pins 95, 96 in the vicinity of said portions 80', 81'. These pins 95, 96 are respectively engageable with the inturned portions 80', 81' by which the rocker 85 is swung or thrown about its pivot 73 into a position in which it is further maintained by the action of said spring 94.

The above described arrangement is designed for forwardly moving the ribbon and winding it on one of said shafts and automatically reversing said ribbon movement after one of the flattened portions 80, 81 functioning as feeler means reaches its lowermost position predetermined by the depletion of the said ribbon on its respective shaft. When one of said feeler portions 80, 81 reaches said lowermost position the respective bent portion of the corresponding bell crank lever is swung into the path of the corresponding pin of the rocker 85 which performs an up- and down-movement together with shield plate 71 during printing operation, and thus tipping or throwing rocker 85 into its opposite extreme position in which the pin 86 engages with a respective leg of U-member 89 and then throwing the lever bar 92 in an opposite direction to bring the respective dog into engagement with its adjacent ratchet wheel.

Fig. 3 shows clearly one extreme position of rocker 85 in which engagement of dog 68 with ratchet wheel 67 is made, while pin 86 engages with leg 88' of U-shaped member 89, thus keeping the other dog 68' out of engagement with its adjacent ratchet wheel 67'. The other extreme position of rocker 85 is indicated by the dotted pin 86' in Fig. 3.

In order to facilitate maintenance of rocker 85 in its respective extreme positions rocker 85 is cut out at its bottom portion to provide the stops 95', 96' against movement of said rocker 85 until the latter is thrown from one to the other extreme position.

The device will be further described in connection with the operation of the machine which follows:

Plate 27 which carries indicia or characters 116 to be imprinted or embossed is slidably inserted into slideways 28 and locked into position, for which latter purpose plate 27 is provided with a perforation 100. Pivotally mounted on abutment plate 59 on lug 62 at 101 is a lever arm 102 which has an arcuate end portion 103 to clear shaft bearing 65'. Portion 103 (Fig. 2) has an inwardly directed extension 104 for engagement with a pin 105 secured to a lug 106. Lug 106 is fixed to a shaft 107 which is rotatably mounted in a bearing 108 provided in the side wall 12. Lug 106 has a further pin 109 utilized as a stop against abutments 110, 111 provided on bearing sleeve 112 to limit swinging movement of lug 106 and thereby rotatable movement of shaft 107 so that pin 105 may be selectively maintained in engaged or disengaged position with respect to lever extension 104. Lever arm 102 has pivoted to it at 113 a downwardly directed pin 114 which is adapted to register with said plate perforation 100 when said plate 27 is placed in operative position in said slideway 28 and this registry is brought about by rotation of shaft 107 as by means of a key 115 inserted within a suitable lock 116 of which shaft 107 forms part. Pin 114 is encompassed by expansion spring 117 interposed between lever arm 102 and top surface of abutment plate 59.

Now, when spring 117 is in expanded position lever arm 102 is in raised position and plate 27 may be removed for pin 114 is not in engagement with perforation 100. When, however, by turning key 115 until pin 105 throws lever extension 104 and thereby lever 102 downwardly in direction indicated by arrow (Fig. 1) pin 114 will register with and protrude within perforation 100, thereby locking plate 27 in its operative position against action of spring 117. It is evident that by turning key 115 in an opposite direction to that aforementioned, plate 27 may be removed, since pin 114 is thereby withdrawn from perforation 100 of plate 27 and retracted within perforation 100' of abutment plate 59.

Plate 27 carries indicia 116 on its undersurface adjacent ribbon 26 (Fig. 1). Now, by inserting a check or other paper P with one of its edges along guide 24 and by turning key 118 of electric switch 119 the device is made ready for operation. This switch 119 may be of any conventional type and design, its purpose being to complete an electrical circuit which includes solenoid 30 in accordance with Figs. 4 and 5 which show diagrams of the wiring connections.

Fig. 4 which shows a simplified wiring system discloses the solenoid 30 which vertically moves upwardly plate 25 through core 29 when switch lock 119 is rotated so that cam 119' is in engagement with terminal 120 of the power supply line thus coming in contact with switch element 121. By now moving paper P along the oblique guide 24 on platform 17 and against switch lever 122, the latter being pivoted at 123 to an extension 124 of the solenoid casing 31 (Fig. 6), the said lever 122 will be swung rearwardly by the paper edge abutting the nose 125 of the said lever, and thus causing insulated finger 126 which is pivoted 70 to the lower extremity of lever 122 at 127 and engaging spring switch element 128, to contact the stationary switch element 129 for completing the circuit and thus energizing solenoid 30. Finger 126 has a reduced free end portion forming 75

a nose 130 which protrudes through an opening 131 of switch element 128. Core 29 carries as aforesaid an arm 42 provided with a pin 132. When core 29 is moved upwardly (after the said circuit is closed) pin 132 abuts the nose 130 of finger 126 and swings the latter upwardly about pivot 127 and thus tripping element 128 free from abutting engagement with finger 126 and breaking the circuit between contact elements 128 and 129.

When the solenoid 30 is energized the platen 25 is forced upwardly carrying with it on its upper surface the paper to be imprinted against ribbon 26 which latter is then pressed against the relief of the indicia thus producing a true replica thereof on the paper.

By breaking said contact between 128, 129 solenoid 30 is deenergized and spring 49 brings platen 25 with the paper P out of engagement with ribbon 26 into its normal inoperative position.

After the impression has been made the paper P is withdrawn from platen 25 and platform 17, thus causing lever 122 to swing back by means of spring 133 (Fig. 6) fixed on pivot 123 and making ready the switch arrangement 126 to 132 for again energizing the solenoid 30 for the next impression. Finger 126 will then assume the position shown in Figs. 4 and 6 (in full lines) with the wall 134 of said finger 126 engageable with the adjacent surface of element 128 while nose 130 protrudes again through slotted opening 131.

In practice it may be found necessary to retard the breaking off of the solenoid circuit to allow sufficient lapse of time to permit a complete and thorough impression of the indicia upon the paper, that is, to produce a lag in the circuit. To this end, provision is made, as shown in Fig. 5, of an arrangement comprising three separate switches 135, 136 and 137. Switch 136 is similar to switch shown in Fig. 4 comprising the contact elements 128, 129. Switch 136 is the make-switch for a relay circuit which includes switch 137. Switch element 129' is connected to the solenoid 30 and to one leg 138 of power line and is further connected to the switch element 139 of switch 135, which is the breaking-switch. The other contact element 140 of switch 135 is resilient and is connected to a terminal 141 of relay switch 137. Another terminal 142 of said relay switch is connected to the solenoid 30 through lead 143.

Resilient switch element 129' is connected to one terminal 144 of the winding of said relay switch, the other terminal 145 of said winding being connected to a terminal 146 of the main locking switch 119 which corresponds to the locking switch 119 (Fig. 3), the other terminal 147 of said switch being connected to the other leg 148 of the power line.

Swingably connected to the relay 137 at 149 is an armature 150 adapted to make electrical contact with terminal 142 upon energization of relay 137; and swingably connected at 144 is another armature 151 which is adapted to make electrical contact with terminal 141 upon said relay 137 being energized.

It will be assumed that switch 119 is made operative so as to close the contact between blade 152 and terminal 146 and that the paper P has been inserted thereby swinging arm 122 compelling contact between elements 128', 129' of switch 136 in a manner heretofore described with respect to Fig. 4. This will cause energization of the relay circuit 148, 147, 152, 146, 145, 150, 151, 144, 128', 129', 138, at the same time ener-

gizing solenoid 30. Energization of the latter causes upward movement of platen 25 until it reaches its uppermost position engaging thereby abutment 153 and raising switch arm 140, opening switch 135 and breaking the circuit. Before this occurs switch 136 has been opened because contact elements 128', 129' have been separated in a manner heretofore described with respect to Fig. 4.

Although the circuit in which switch 136 having said contact elements 128', 129' is placed, was just opened, the circuit including leads 148, 147, 152, 146, 145, 150, 142, 143, solenoid 30, 138 and leads 148, 147, 152, 146, 145, 144, 151, 141, 140, 139, 129', 138 is still closed until the circuit breaking switch 135 is opened which will take place when platen 25 comes in contact with abutment 153, that is, in the uppermost position of platen 25 when a complete and thorough impression is performed by the latter. Upon engagement of platen 25 with abutment 153, switch 135 is opened and relay switch 137 is thus de-energized, as well as the solenoid 30.

Platen 25 will thereafter return to its initial inoperative position through action of spring 49, ready to be raised again upon actuation of lever 122 by insertion of another paper upon which an impression is to be made.

Fig. 7 shows a modified and combined electric and plate lock arrangement which consists of a member 150 having a cam 151 at one of its ends and a pin 152 (similar to pin 105) at its other end. Member 150 corresponds to part 106 of Fig. 2. Member 150 is rotatable with shaft 153 in such manner that by rotation of shaft 153 (as by means of a lock key, not shown) cam 151 will break contact between elements 120', 121' whereas pin 152 disengages from lever 104' and thus permitting unlocking of indicia plate 27 from pin 114 as hereinbefore described.

Of course, it is understood that locking of plate 27 will take place when member 150 is returned to the position indicated in Fig. 7.

It is further understood, that a counter and a date stamp (not shown) may be provided in order to keep record of the number and dating of checks etc. impressed with the indicia. A conventional counter 160 may be positioned at the front part of the device, as on a plate 161 and may be actuated through a leverage 162 by shaft 56, with which said leverage is connected. Lever 163 forming part of leverage 161 is fixed to shaft 56, so that when impression is made by lifting lever 48 (Fig. 6) shaft 56 will then be swung and thus movement thereof will be transferred to lever 163 and leverage 161 for the conventional actuation of counter 160.

The device is protected against mishandling, dust and injury by a cover 14 which is made removable and may be locked to the base 11 by a conventional lock 164.

Below platform 17 at the front of said device is a removable wall plate 165 to enable access being gained to the lower part of said device. This wall is attachable to the side walls 12, 13 as by means of screws (not shown) which threadedly engage said walls within holes or bores 166.

From the above description it will be apparent that there is thus provided a device of the character described possessing the particular features of advantages before enumerated as desirable, but which obviously is susceptible of modification in its form, proportions, detail construction and

arrangement of parts without departing from the principle involved or sacrificing any of its advantages.

While there has been shown and described and pointed out the fundamental novel features of the invention as applied to preferred embodiments, it will be understood that various omissions and substitutions and changes in the form and details of the device illustrated and its operation may be made by those skilled in the art without departing from the spirit of the invention.

Having thus described the invention, what is claimed as new and desired to be secured by Letters Patent, is:

1. In a device of the character described having a reciprocably movable platen; a removably arranged element carrying printing indicia, an electric circuit including switch means, a controller and electric means for operating said platen, and common actuating means adapted to lock said element in position and to concurrently close said switch means, said controller being adapted to operate said electric means in said electric circuit when said switch means has been previously closed by said actuating means.

2. In a device of the character described having a reciprocably movable platen; a removably arranged element carrying printing indicia, an electric circuit including switch means, a controller and a solenoid having a plunger for operating said platen, and common actuating means adapted to lock said element in position and to concurrently close said switch means, said controller being adapted to operate said solenoid in said electric circuit when said switch means has been previously closed by said common actuating means.

3. In a device of the character described having a reciprocably movable platen; a removably arranged element carrying printing indicia and having an opening, an electric circuit including switch means, a controller and electric means for operating said platen, a leverage extending between said switch means and said element, and common means adapted to actuate said leverage whereby a portion of the latter registers with said opening of said element to lock the same in position, whereas another portion of said leverage engages with said switch means to concurrently close the same, said controller being adapted to operate said electric means in said electric circuit when said switch means has been previously closed by said common actuating means.

4. In a device of the character described having a reciprocably movable platen; a removably arranged element carrying printing indicia and having an opening, an electric circuit including switch means, a controller and electric means for operating said platen, a leverage extending between said switch means and said element, and key controlled common means adapted to actuate said leverage whereby a portion of the latter registers with said opening of said element to lock the same in position, whereas another portion of said leverage engages with said switch means to concurrently close same, said controller being adapted to operate said electric means in said electric circuit when said switch means has been previously closed by said key controlled common means.

GERHARD G. GRUETTNER.
